Alex. Salkirk

UNITED STATES PATENT OFFICE.

LEVI C. STRONG, OF ALBANY, NEW YORK.

SASH-HOLDER.

SPECIFICATION forming part of Letters Patent No. 244,405, dated July 19, 1881.

Application filed July 13, 1880. (No model.)

To all whom it may concern:

Be it known that I, LEVI C. STRONG, of the city and county of Albany, and State of New York, have invented certain new and useful 5 Improvements in Locks for Sashes, of which the following is a specification.

My invention relates to improvements in sash-locks in which a cam made in the form of a section of a spiral screw-thread operated 10 by a lever is made to operate a locking-bolt to throw it forward to crowd it against the jamb or draw it back, as may be selected.

The object of my invention is to operate the locking-bolt in opposite directions by means 15 of a spiral cam provided with a finger-lever, which lever will operate as a means for holding the sash from suddenly falling when the sash is being unlocked. I attain this object by means of the several parts and devices illustrated in the accompanying drawings, in which—

Figure 1 represents sections of a jamb and a sash and a perspective view of the sash-lock. Fig. 2 is a plan view from the lower side of the device. Fig. 3 is a side elevation of the same. Fig. 4 is a view taken in the transverse at line No. 1 in Fig. 3. Fig. 5 is a perspective view of the locking-bolt. Fig. 6 is a perspective view of the cam and its finger-lever, and 30 Fig. 7 is a plan view of the retaining-piece.

Similar letters refer to similar parts throughout the several views.

In the drawings, A is the jamb of the casting, in which the sash B works freely in either 35 direction vertically. Secured to the said sash, as shown in Fig. 1, is my improved locking device, composed of the locking-bolt C, cam D, with finger-lever E, and retaining-plate F. The locking-bolt C is made in the form shown 40 in Fig. 5, with sliding part a, serrated head b, and notch c. The cam D is made in the form of a section of a spiral or screw thread on a hub, and is provided with pintles d d, on which the said cam works. Made with said cam is 45 the finger-lever, by which lever the cam is operated. The retaining-plate F is made in the form shown in Fig. 7, and is provided with the orifice f, having a width corresponding with the length of the hub of the cam D and 50 an extension of length corresponding with the diameter of said cam. Made solid with said plate, and extending downward from the lower

side of the same, are the bearings e e, which receive pintles d d of the cam. Made also with said plate, and on its lower side, is the guiding way or flange g, against which the sliding part a moves when said locking-bolt is operated. The said plate is also provided with countersunk holes for receiving screws s, for securing the said plate and all the parts of my improved 60 device in place with the sash. These parts—the locking-bolt C, cam D, and its finger-lever E and retaining-plate—are arranged together in the manner substantially as shown in Figs. 1, 2, 3, and 4, and secured in their respective 65 places in the sash B.

To place the several parts in proper order in the sash, the edge of one of the side rails of the sash is recessed to receive the head b of the locking-bolt. The face side of the sash is 70 also recessed to receive the sliding portion of said bolt, as shown in Figs. 1 and 4. Another and deeper recess, m, is made in the face side of said sash, as shown in Figs. 3 and 4, which recess receives the cam D. The locking-bolt 75 will then be placed by entering its sliding part in the recess on the face of the sash and its head portion in the recess in the edge of the same. The cam D is then placed in its recess m, with the spiral portion entering notch c made 80 in the locking-bolt. The retaining-plate F will then be slipped over the finger-lever E of the cam and turned quarter around, so as to cause the bearings e e to receive pintles d d of cam D, and the guiding-flange g to bear against 85 the edge of the sliding part a of bolt A, opposite from the edge having notch c, as indicated by dotted lines in Fig. 1, and shown by full lines in Figs. 2 and 3.

When it is desired to lock the sash at any 90 place moved to, the operator will only be required to press the finger-lever downward toward the sash, when the spiral cam will work against the side of notch c, toward head b of the locking-bolt, and force the said bolt with 95 great pressure forward, so as to cause the serrated head to bear against the jamb A. This will cause the opposite side rail of the said sash to press against its jamb, when the sash will be locked from moving.

When it is desired to unlock the sash the operator will throw the finger-lever upward, when the cam will be turned, and will cause the spiral portion to bear against the side of

notch *c* of the bolt, so as to carry said bolt back and draw its serrated head from contact with the jamb, when the sash may be moved.

It will be readily observed that the cam, 5 when operated to throw the locking-bolt forward to hold it against the jamb, will receive the resistance in a direction parallel with the axis on which it revolves, and that no amount of pressure exerted on the said cam through 10 the locking-bolt will be capable of causing the same to be turned back.

It will also be readily observed that when the operator throws the finger-lever *E* upward to throw the locking-bolt back, the instant the 15 said locking-bolt is off from contact with jamb *A* the sash (not supported by counterbalancing-weights) would naturally fall, and that the upward lifting of the finger-bolt will check the fall of the sash as the operator exerts an 20 upward pressure on said finger-lever, and that the operator may by said lever permit the sash

to slowly descend, or he may raise the same to a higher plane.

It will also be observed that the retaining-plate, by means of the orifice *f* and bearings 25 *e e*, retains the cam in place from shifting, and by means of the guiding-flange *z* holds the locking-bolt in place so as to freely move when the cam is operated.

What I claim, and desire to secure by Letters Patent, is—

In a sash-lock, the combination, with the retaining-plate *F*, provided with bearings *e e*, orifice *f*, and guiding-flange *z*, of the cam *D*, made in the form of a section of a spiral or 35 screw thread, and provided with finger-lever *E*, and the locking-bolt *C*, provided with notch *c*, substantially as and for the purpose set forth.

LEVI C. STRONG.
